(57) **CLAIM**

I claim the ornamental design for a table leg, as shown and described.

DESCRIPTION

FIG. 1 is a perspective view of a table leg, showing our new design;

FIG. 2 is right side elevational view;

FIG. 3 is a left side elevational view;

FIG. 4 is a front elevational view;

FIG. 5 is a rear elevational view;

FIG. 6 is a top plan view; and,

FIG. 7 is a bottom plan view thereof.
